(57) **CLAIM**

The ornamental design of a carafe, as shown and described.

DESCRIPTION

FIG. 1 is a perspective view from the top and one side of my carafe design;

FIG. 2 is a perspective view from the bottom and an opposite side of my carafe design;

FIG. 3 is a side elevation of my carafe design, it being understood that a side elevation of the opposite side is a mirror image of this FIG. 3;

FIG. 4 is a front elevation of my carafe design;

FIG. 5 is a side elevation of my carafe design;

FIG. 6 is a top plan view of my carafe design; and,

FIG. 7 is a bottom plan view of my carafe design.
